UNITED STATES PATENT OFFICE.

FRANK J. CLIFFORD, OF EVANSTON, ILLINOIS.

JOINTED FRAME.

1,187,969.

Specification of Letters Patent. Patented June 20, 1916.

Application filed July 10, 1914. Serial No. 850,237.

To all whom it may concern:

Be it known that I, FRANK J. CLIFFORD, a citizen of the United States, residing at Evanston, in the county of Cook and State 5 of Illinois, have invented a certain new and useful Improvement in Jointed Frames, of which the following is a specification.

When advertisements are printed upon sheets of flexible material, usually paper or 10 board, and when ordinary sticky fly paper is to be placed in position for use, it is desirable to provide a suitable frame for the protection of the paper, and to, at the same time, make the frame flexible so that the advertisement or fly paper can be displayed in 15 other than the ordinarily perfectly flat position. Such a frame is specially desirable when the advertisement or fly paper is to be applied in an exposed position, such as that 20 which exists above a cash register or money scale in a grocery or market.

The object of this invention is to provide such a flexible frame which can be easily and cheaply made, which operates satisfac- 25 torily and is not readily liable to get out of order.

The invention consists in a device capable of carrying out the foregoing objects, which can be so adjusted as to support the same in 30 either a circular or a semi-circular position, and in other details of construction which will be fully described in the specification.

Referring to the drawings, in which similar numerals indicate the same parts 35 throughout the several views, Figure 1 is a side view of mechanism illustrating this invention in its preferred form, the same showing all the parts, including the fly paper in normal position ready for use. Fig. 40 2 is a sectional detail view on the line 2—2, Fig. 1. Fig. 3 shows the parts of Fig. 2, the band 12 being detached at its pivot end, this, however, not being the normal operation of the device. Fig. 4 is a sectional detail view 45 on the line 4—4, of Fig. 1. Fig. 5 is a plan view partially in section taken on the line 5—5 of Fig. 2. Fig. 6 is a perspective view showing the entire device supporting the paper in a semi-circular position instead of 50 the circular position of Figs. 1, 2 and 3. Fig. 7 is a changed position view of the parts in Fig. 6, showing the normal method of detaching the outer bands 12.

Broadly speaking, the frame of this in- 55 vention consists in two parallel members 10 identical in construction, adapted, normally,

to engage the longer sides of the paper, the same being connected together at their opposite ends by flexible parallel bands 12 and 14—14^a adapted to engage and frame the 60 ordinarily shorter ends of the paper 16, the whole device being readily adjustable to either the position of Figs. 1, 2 and 4 in which the paper 16 assumes a cylindrical form or to that of Figs. 6 and 7 in which 65 the paper assumes a semi-circular position.

More in detail, the preferred form of construction includes the two parallel members 10 and 11, preferably made, as shown, V shaped with hollow beads 18, 20 and 22 70 located respectively at their bottoms and two upper edges. The space between the side walls of the V members receive, hold and protect the edges 24 of the paper 16. As heretofore stated, the end members of 75 the frame are made up of two parallel flexible bands 12 and 14. The outer band is pivoted on any suitable pivot 26 to one of the side members. In the particular case here illustrated, the pivot 26 is one side of a U 80 shaped coupler whose opposite side is loosely inserted in bead 22 of member 10. The opposite end of the band 12 is provided with a spring clip device 28 (see particularly Figs. 2 and 3) adapted, as shown, to snap over 85 and engage the bead 18 on the same member 10 to which the band 12 is pivoted. This band 12 also detachably engages and grips the opposite member 10 in the curved snap device 30, clearly shown in Figs. 2, 3 and 6. 90

The result of the foregoing construction is that by detaching the snap hook 28 from the member 10 the band 12 may be moved from the position shown in Figs. 1 and 2 to that of Figs. 6 and 7, and by then unsnapping the snap device 30 from the member 11 the band 12 may be moved from the full line position of Fig. 7 to the dotted line position of that figure, with the result that when both bands 12 are thus treated the paper 16 may be removed from the device. Supplemental U shaped couplings 32 may also be inserted in the opposite ends of bead 18 of members 10 and 11. 95

The inner band 14 is made in two parts, 105 14 and 14^a, each part having its outer end attached to one of the side frames 10 or 11 and their inner ends are pivotally connected together by any suitable form of pivot de- 110 vice which will permit of the band assuming the various positions shown in the drawings, the parallel link pivot 34 being only one of

numerous conceivable devices which could be used in this way. In the particular case here shown the outer ends of the half bands 14 and 14^a are attached to the side frames by being provided with end loops 33 slidable inside the beads 18. This provides ready separability of the parts when desired.

When the parts are in the position of Figs. 6 and 7, the central pivotal ends of the band portions 14 and 14^a form each of them one leg of the support of the device.

When the parts are in the position shown in Figs. 1, 2 and 4, independent supports or standards 36 may be provided. The particular form shown is provided with gripping jaws 38 pressable together by a slidable member 40 so that they can be readily attached and detached.

In the normal operation of the device, assume the parts are initially in the position shown in Fig. 7. The paper 16 is inserted in position and the parts are then adjusted in the position shown in Fig. 6 in which position the device may be practically used. If, however, the operator desires to have the paper in circular form, he, by proper and obvious manipulation, moves the parts from the position of Fig. 6 to that of Figs. 2 and 3, inserting finally the U-shaped members 32 and attaching, if desired, the supporting standards 36, the U-shaped members 32 being only one of numerous conceivable devices that may be used to secure the frame in a circular form. When the paper 16, previously inserted, has reached its limit of usefulness, it is removed by reversing the operations just described, and new paper is inserted.

Fig. 3 shows how the paper may be removed when the parts are in the position of Fig. 1 by removing from the opposite ends of the device the U-shaped pins 26 and thus releasing the outer band 12 without disturbing the other parts.

For convenience of description, the members 10 and 11 are referred to in the specification and claims as "side" members, and the bands 12 and 14—14^a are referred to as "end members", but, obviously, these terms as well as the relative lengths of these respective parts may be reversed without departing from the invention.

What I claim is:

1. In the art described, a frame inclosing an open central portion having side members and end members adapted to receive and protect the edges of a sheet of material framed therein extending over said open central portion, one of said sets of members being flexible, for the purposes set forth.

2. In the art described, the combination of a frame inclosing an open central portion composed of rigid side members and flexible

end members adapted to receive and protect the edges of a sheet of material extending over said open central portion, in combination with means for securing the two side members in proximity to each other when the end members have been suitably bent.

3. In the art described, a pair of rigid side members recessed to receive the edges of a sheet of material to be held, means for detachably securing said side members in proximity to each other, flexible end members connecting adjacent opposite ends of the side members, said end members being composed of two parallel flexible bands, each having its outer end connected to one of the side members in such manner that the ends of the sheet of material may be inserted between each pair of flexible bands, for the purposes set forth.

4. In the art described, a pair of side members, a pair of parallel flexible bands connected at their opposite ends to adjacent ends of the side members, and a hinge device intermediate of the ends of one of said flexible bands so arranged that said last mentioned flexible band may be removed to a position in which said hinge device lies in a plane through the side members thereby forming a three-point support for that end of the entire device.

5. In the art described, a pair of rigid side members parallel to each other, a pair of flexible end members at right angles to the side members and connecting opposite ends of said side members, each end member comprising a pair of parallel flexible bands between which an end of the sheet to be framed in the device is to be inserted, a pivotal connection between one of said bands and its adjacent side member, and means for detachably connecting the opposite end of said band to its adjacent end of the side member, for the purposes set forth.

6. In the art described, the combination of two parallel side members, a flexible end member connecting the adjacent ends of said side members, said end member comprising two parallel flexible bands, one of them being made in two parts hinged together at their inner or central ends and connected at their outer ends to the side members, the other band being pivoted at one end to one of the side members and detachably connectible at its opposite end to the opposite adjacent side member, for the purposes set forth.

In witness whereof, I have hereunto subscribed my name in the presence of two witnesses.

FRANK J. CLIFFORD.
